(57) **CLAIM**

I claim the ornamental design for a bird feeder shelter, as shown and described.

DESCRIPTION

FIG. 1 is a perspective view of the bird feeder shelter shown in a usage state in an environmental view.

FIG. 2 is a right side view of the claimed design.

FIG. 3 is a left side view of the claimed design.

FIG. 4 is a front view of the claimed design.

FIG. 5 is a back view of the claimed design.

FIG. 6 is a top view of the claimed design; and,

FIG. 7 is a bottom view of the claimed design.

The broken lines shown in FIG. 1 illustrate environmental structure. The broken lines shown in FIG. 7 illustrate portions of the bird feeder shelter. The broken lines form no part of the claimed design.

1 Claim, 7 Drawing Sheets(56)
